UNITED STATES PATENT OFFICE.

CARL G. HASSMANN, OF CHICAGO, ILLINOIS, ASSIGNOR TO MILLS NOVELTY COMPANY,
OF CHICAGO, ILLINOIS, A CORPORATION OF ILLINOIS.

VENDING-MACHINE.

1,028,458.

Specification of Letters Patent.

Patented June 4, 1912.

Application filed April 1, 1912. Serial No. 687,747.

To all whom it may concern:

Be it known that I, CARL G. HASSMANN, a citizen of the United States, residing at Chicago, in the county of Cook and State of Illinois, have invented a new and useful Improvement in Vending-Machines, of which the following is a specification.

My invention relates to an improvement in vending machines which I have especially devised for vending, one at a time, drinking-cups from a stack thereof in which the cups are nested one upon the other; though it may be used for vending other articles requiring similar operation for effecting their delivery from the machine.

The cups, in the present instance, which are of the variety come to be known as sanitary drinking cups, are made of waterproof paper, preferably thin, paraffined paper, molded into cups of circular cross-section and tapering from their open ends, which are circumferentially flanged, to their closed ends. These cups are nested together in a stack to form a narrow space between the flanges of successive cups, and the stack, which is confined within a suitable housing or magazine, preferably a glass or transparent cylinder, rests at its base in the path of normally inoperative delivery-mechanism, which is rendered operative, to effect the delivery, through the medium of a coin, representing the purchase price, by inserting it into the machine.

The present invention relates, primarily, to the construction of the delivery-mechanism, my object being to render that mechanism positive and reliable in its operation, simple and durable.

In the accompanying drawings, Figure 1 shows the machine by a view in vertical sectional elevation, with the upper part of the magazine broken away, the section being taken on line 1, Fig. 2; Fig. 2 is a section on line 2, Fig. 1, showing the parts of the delivery-mechanism in the relative positions they assume upon inserting a coin preparatory to operating the machine; Fig. 3 is a similar view, but omitting the coin-chute, showing the parts of the delivery mechanism in their normal condition, or relative positions to which they are brought by operating the machine; Fig. 4 is a section on line 4, Fig. 2, and Figs. 5 and 6 are sections, respectively, on lines 5 and 6, Fig. 3.

For supporting the mechanisms, the drawings show a mere base 7 with a back 8

rising from one end thereof, though any suitable support may be used. To the base and back is secured the curved bottom of a metal chute 9 having a delivery-opening at 10 and a top 11 provided on its forward end with a depending flange 12 and on its rear end with a depending flange 13 through which latter the chute-bottom is secured to the back 8. At one side of the delivery-chute, and conforming to that side, is provided a chamber 14 closed by a cover 15 (Figs. 5 and 6) forming the outer chamber-wall and equipped with a suitable key-operated lock 16, by which to removably secure it in place. In this chamber, near its forward upper end, is fulcrumed at one end a lever 17 terminating at its opposite end in a socketed head 18 for receiving edgewise a coin 19; and the lever is held in its normally-raised horizontal position by a spring 20 depending from the chute-top 11, which also forms the top of the chamber 14. The top, which is provided near the opposite lateral edges of its upper surface with parallel guide-flanges 21 and 22, contains a central circular feed-opening 23 having a rear oblique notch or recess 24, and a forward elongated slot 25 extending parallel with and adjacent to the guide 21 and having a rear offset section 26; and in the chute-top is formed, back and to one side of the delivery-opening 23, a curved slot 27 for limiting the movement of a stud 28 projecting upwardly through it from one end of a lever 29 fulcrumed between its ends to the under face of the top and terminating at its opposite end in a cup-supporting head 30 coincident with the notch 24 and normally retracted into the latter by a spring 30' controlling the lever.

A slide-member 31 fits, to be reciprocated on the top 11, between the guides 21 and 22, and is automatically retracted to its inward position, represented in Fig. 2, by a spring 32 connecting it, from one edge near its forward end, with the guide-flange 21 near its rear end. This member is shown in its preferred form of a generally-rectangular frame having an upturned handle 33 centrally on its forward end and a lug 34 depending from near one edge through the slot 25 into the path of the socketed head 18 on the lever 17 (Fig. 4), that head registering with the slot-section 26. The forward end 35 of the frame-opening is crescent-shaped and has a tongue 36 projecting rearwardly and cen-

trally from it, and the rear end of the frame includes a slightly-elevated cross-bar 37 having parallel fingers 38 projecting forwardly from its opposite ends, these fingers being beveled on their lower edges near their forward ends to better adapt them to dislodge a drinking-cup by engaging its flange, as hereinafter described. The slide-frame also contains an elongated edge-recess 39 to register with the slot 26 in the retracted position of the frame, and is provided on its upper surface, adjacent to that recess, with a rack 40 and in advance of the rack with an aperture 40¹.

15 A rectangular cap 41 seats on the top 11 to cover the mechanism on the latter, and it contains a central circular opening 42 formed with a sleeve 43 extending through it and seating at its lower edge against the frame 31, whereby it is in the path of the dislodging-fingers 38, which, however, work through slots 44 in their path, formed in that end of the sleeve to register with the fingers. The upper projecting end of this sleeve has secured about it the lower end of a cylinder 45, preferably of glass and forming a magazine rising from the cap, which is furthermore provided with a central recess 46 in its forward end to admit the handle 33

25 in the rearward movement of the slide-frame.

Near one edge of the cap 41 is supported a coin-chute 47 to extend over the chamber 14 and register at its discharge-end with the recess 39, and thus also with the slot 26 and lever-head 18. The mouth or coin-insertion end of this chute has extended across it the laterally-deflected end 48 of a vertical rod 49 supported by a spiral spring 50 confined about it, the rod working through guide-lugs 51 projecting from the inner side of the chute. This rod, which forms a stop, extends downwardly through a hole 52 in the cap 41 into the path of the forward edge of the slide-frame 37, shown beveled at 53 in Fig. 4, and into the path of the hole 40¹. The coin-chute also carries on its inner side a spring-pressed pawl 54 to engage the rack 40, being pivoted to permit the rack 50 to pass it freely in either direction of movement of the slide-frame but to lock the latter at any intermediate position of the movement of the frame by engaging the rack, thus to prevent reverse movement of the frame from any such position.

The drinking-cups 55 are formed with outwardly-flaring flanges 56 about their open ends, at which they are nested together, as shown in Fig. 1, to form a stack in the magazine extending through the sleeve 43 and seating, at the flange of the lowermost cup, which is in position to be overridden by the dislodging fingers 38, upon the forward end 35 of the slide-frame and the lug 65 or head 30.

The operation is as follows: With the delivery-mechanism in its normal condition represented in Fig. 3, the frame 31 is in its outermost position, with the rod 49 depressed by its spring into the hole 40¹ to prevent the spring 32 from retracting the frame. By the movement of the slide-frame which brought it to that position, its end 35 and tongue 36 were withdrawn from underneath the stack of cups and the engagement of the slot 27 with the stud 28 turned the lever 29 to withdraw the head 30 from its stack-supporting position into the recess 24; but the fingers 38 were thereby advanced underneath the stack to support it. The machine is thus in readiness to be operated upon the insertion of a coin 19 into the chute 47. The diameter of a coin of proper denomination is greater than the height of the insertion-mouth of the coin-chute up to the end 48 of the rod 49 crossing it, so that by the act of insertion the coin, in clearing the rod-end in its path, lifts the rod 49 out of the hole 40¹ and thus unlocks the slide-frame, thereby freeing the spring 32 to retract it to its innermost position, shown in Fig. 2. In that position the frame-end 35 and tongue 36 and the head 30, under the action of its controlling-spring 31, are below the stack of cups, which drops to rest upon them by the withdrawal from underneath it of the fingers 38, which then register with the space immediately above the flange of the lowermost cup. In the last-described condition of the parts, the frame 31 would still remain obstructed against withdrawal by a shoulder 17¹ on the lever 17 in the path of the lug 34 depending from the frame. However, when the inserted coin, rolling edgewise through the chute 47, has dropped into the socket-head 18, the depth of which is only sufficient to take about one-half the width of the coin, the upper portion of the latter extends through the slots 26, 39, by which it entered that socket; so that by pulling outwardly on the handle 46 the coin is pressed against the forward edge of the slot 26 to force the head 18 downwardly and thereby turn the shoulder 17¹ out of the path of the lug 34 and permit the frame to be fully withdrawn. The tilting of the lever 17 throws the coin out of the socket into the chamber 14, and the spring 20 thereupon returns the lever to its normal position.

By the withdrawal of the slide-frame, the fingers 38 override the flange of the lowermost cup and depress it out of the stack to drop through the feed-opening 23 into and be delivered through the chute 9, the fingers meantime supporting the remainder of the stack until the machine is again operated to retract them and present the portion 35 of the frame and tongue 36 thereon, and the head 30, to support the stack when

it drops upon them by gravity to register the space above the then lowermost cup-flange with the fingers. When the slide-frame has been thus fully withdrawn to effect the delivery, its hole 40¹ then registers with the rod 49 to permit the spring 50 to depress it into that hole and lock the delivery-mechanism for the next operation of the machine by the insertion of a coin.

10 I realize that considerable variation is possible in the details of construction thus specifically shown and described, and I do not intend by illustrating a single, specific, or preferred form to limit my invention thereto; my invention being in the following 15 claims to claim protection upon all the novelty there may be in the device as broadly as the state of the art will permit.

What I claim as new and desire to secure 20 by Letters Patent is:—

1. In a vending machine of the character described, the combination of a delivery-chute having a feed-opening in its top, a spring-retracted slide-member supported on 25 said top and provided with an opening, forwardly-projecting delivery-fingers on the slide-member traversing said feed-opening by forward movement of said member, and means for releasably locking the slide-member in its forward withdrawn position.

2. In a vending machine of the character described, the combination of a delivery-chute having a feed-opening in its top provided with a rear recess, a spring-retracted 35 slide-frame supported on said top and having a forward stack-seating section, forwardly-projecting delivery-fingers on said frame traversing said feed-opening by forward movement of the frame, a spring-pressed supporting head retractable into 40 said recess by forward movement of said frame and coöperating with said seating section, and means for releasably locking said frame in its forward withdrawn position.

3. In a vending machine of the character described, the combination of a delivery-chute having a feed-opening in its top, a spring-retracted slide-frame supported on 50 said top and having a raised rear-end cross-bar, delivery-fingers projecting forwardly from said cross-bar near opposite sides of the frame to traverse said feed-opening by forward movement thereof, and means for 55 releasably locking said frame in its forward withdrawn position.

4. In a vending machine of the character described, the combination of a delivery-chute having a feed-opening in its top provided with a rear recess, a spring-retracted 60 slide-frame supported on said top and having a forward stack-seating section and an

elongated slot, delivery-fingers projecting forwardly from the rear end of the slide-frame to traverse said feed-opening by forward movement of said frame, a spring-pressed lever having a head on one end co-operating with said seating-section and retractable into said recess, and a stud on its opposite end projecting into said slot, and means for releasably locking said frame in its forward withdrawn position.

5. In a vending machine of the character described, the combination of a delivery-chute having a feed-opening in its top, a spring-retracted slide-member supported on 65 said top and provided with an opening, forwardly-projecting delivery-fingers on the slide-member traversing said feed-opening by forward movement of said member, a cap on said top having an opening with a sleeve depending therein in the path of said fingers and provided with openings for their passage therethrough, and means for 70 releasably locking the slide-member in its forward withdrawn position.

6. In a vending machine of the character described, the combination of a delivery-chute having a feed-opening in its top, a spring-retracted slide-frame supported on 75 said top having an aperture, forwardly-projecting delivery-fingers on said frame traversing said feed-opening by forward movement of the frame, a cap on said top provided with an opening for the articles to be 80 delivered, and a spring-depressed rod projecting through the cap to register with and enter said aperture in the forward withdrawn position of said frame and releasably 85 lock it therein.

7. In a vending machine of the character described, the combination of a delivery-chute having a feed-opening in its top provided with a rear recess, a spring-retracted 90 slide-frame supported on said top and having a forward stack-seating section, forwardly-projecting delivery-fingers on said frame traversing said feed-opening by forward movement of the frame, a cap on said top provided with an opening for the articles to be 95 delivered, and a spring-depressed rod projecting through the cap to register with and enter said aperture in the forward withdrawn position of said frame and releasably 100 lock it therein.

8. In a vending machine of the character described, the combination of a delivery-chute having a feed-opening in its top provided with a rear recess, a spring-retracted 105 slide-frame supported on said top and having a forward stack-seating section, forwardly-projecting delivery-fingers on said frame traversing said feed-opening by forward movement of the frame, a cap on said top having an opening with a sleeve extending through it and provided in its lower section with openings for the passage of said fingers, a magazine rising from said top about the upper projecting portion of said sleeve, and means for 110 releasably locking the slide-frame in its forward withdrawn position.

CARL G. HASSMANN.
